DESIGN FOR A CLOSURE HOOD FOR MILK AND CREAM BOTTLES

Don Ray, Beverly Hills, Calif.

Application October 21, 1944, Serial No. 115,906

Term of patent 14 years

(Cl. D58—26)

To all whom it may concern:

Be it known that I, Don Ray, a citizen of the United States, residing at Beverly Hills, in the county of Los Angeles, State of California, have invented a new, original, and ornamental Design for a Closure Hood for Milk and Cream Bottles, of which the following is a specification, reference being had to the accompanying drawing, forming part thereof.

Fig. 1 is a side elevational view of a closure hood for milk and cream bottles, showing my new design.

Fig. 2 is a top perspective view thereof.

I claim:

The ornamental design for a closure hood for milk and cream bottles, substantially as shown.

DON RAY.
